FRANK W. MERRICK, OF BOSTON, MASSACHUSETTS, ASSIGNOR TO UNION LOCK STITCH COMPANY, OF BOSTON, MASSACHUSETTS, A CORPORATION OF MAINE.

METHOD OF MANUFACTURING SHOES.

1,093,563.

Specification of Letters Patent. Patented Apr. 14, 1914.

Original application filed May 20, 1911, Serial No. 628,379. Divided and this application filed December 17, 1913. Serial No. 807,240.

To all whom it may concern:

Be it known that I, FRANK W. MERRICK, a citizen of the United States, residing at Boston, in the county of Suffolk, State of Massachusetts, have invented a certain new and useful Improvement in Methods of Manufacturing Shoes, of which the following is a specification, reference being had therein to the accompanying drawings.

The present invention is a division of that of my application for U. S. Letters Patent for improvements in welt shoes and insoles for same, filed May 20, 1911, Serial No. 628,379, and consists in the novel and improved method of manufacturing welt shoes by which I produce the shoe that is shown, described and claimed in the said application. The said shoe bears a resemblance structurally to shoes of the Goodyear welt type, in that it has a welt which is attached by means of an inseam to an upper and an insole, and to which an outer sole is attached by means of an outseam. It has the appearance and all of the desirable characteristics of a shoe of the said type, including the snug fit, shapeliness, and durability thereof, while at the same time it is so constructed as to be free from certain drawbacks of shoes of the said type as heretofore made, and is an improvement upon such shoes. It possesses the ease and comfort, and the smooth and flexible tread, of a shoe of the stitch-down type.

By my improved and novel method the operations of manufacture are simplified, the number of operations are reduced, and certain machines and parts of machines at present in use in the manufacure of Goodyear welt shoes are dispensed with. My method produces a shoe in which are secured certain results which are not secured in shoes of the Goodyear welt type as at present manufactured, or in shoes of any other type.

Briefly stated, in proceeding according to my method of making a welt shoe my first step consists in producing an insole by taking a thin flexible insole-blank and forming an upstanding edge-flange or lip thereon by a bend around the margin of the said blank defining the extreme outer boundary of the tread-surface of the insole, and so that a continuation of the said tread-surface forms the exterior of the flange or lip at the bend. I then apply the prepared insole to the cen-

tral portion of the tread-surface of a last with the marginal portion of the latter tread-surface projecting outwardly beyond the outer margin of the tread-surface of the insole. I apply an upper to the last and bend it around the edge of the last, drawing it inward upon the exposed marginal portion of the tread-surface of the last to and against the said continuation of the insole tread-surface immediately at the bend. I then apply a welt, stitch the inseam, trim the inseam, apply an outsole, and connect the outsole with the welt by an outseam.

In the practice of my method I usually make the insoles of cloth, which is not adapted to be channeled or grooved to form a lip or shoulder to receive the stitches of an inseam, or of thin flexible material lacking the thickness requisite to permit the channeling or grooving. This choice of materials conduces to great flexibility and pliability of the finished shoes, and permits a material saving in cost. An insole made by the steps forming a portion of my method has no feather continuing the tread-surface of the insole outward beyond the edge-flange or lip which receives the inseam-stitches.

In order to secure an underset inseam with the upper overhanging and bulging outward past the inseam so as to give the proper shape and appearance to the shoe, I employ a last having a rounded or chamfered marginal reduction around the tread-surface of its sole. The said marginal reduction or chamfer is located inward relative to the laterally bulging body of the last so that after the insole has been applied to the central portion of the sole of the last, and the upper has been applied to the last, the operation of drawing the upper inward to the flange or lip of the insole will bend the upper inward around the exposed rounded or chamfered margin of the sole, and the marginal reduction of the last will afford the necessary clearance to enable the stitch-forming devices, of the sewing machine by which the inseam is stitched, to form the inseam at a point inwardly-located upon the tread-surface of the sole of the last.

The steps of my method are illustrated in the drawings, in which,—

Figure 1 shows in perspective the insole with its molded flange. Fig. 2 is a view thereof in cross-section on line 2, 2, of Fig.

1. Fig. 3 shows in vertical cross-section an upper containing a last, and having combined therewith the insole of Figs. 1 and 2 and a welt, the said welt and the upper being attached to the molded flange of the insole by a line of stitches constituting the inseam. Fig. 4 shows the parts of Fig. 3 after the margins of the welt, upper, and molded flange of the insole have been trimmed away close to the inseam. Fig. 5 shows the parts after the outer sole and cushion or filler have been combined therewith, with the outer sole connected to the welt by the outseam.

15 Referring to the drawings, as above referred to, I subject the blank for the insole 1 to an operation by which its marginal portion is molded to form the upstanding flange 2. The angle, which the flange is caused to assume with relation to the plane of the tread-surface of the insole may vary in practice. In producing the insole, I take a blank of proper size, of a thin flexible material, and form the flange thereon by a simple bending of the marginal or edge-portion of the blank so as to cause it to stand at the required angle to the said plane, and by means of the bending operation I cause the flange to become set in the desired position.

20 30 Along the line of the bend, the insole is without any channel or groove, and consequently the entire thickness of the marginal portion of the insole along the line of the bend is included in the bend. The outer face of the flange is a continuation of that surface of the body-portion, *i. e.*, intermediate portion of the insole, which in the lasting operation faces the sole of the last 4, and which during the wearing of the shoe receives the direct pressure of the wearer's foot. Consequently, the insole has no so-called feather.

25 In Figs. 3, 4, 5, the upper is marked 3, and 4 is the last within the upper, 5 being the welt. A lining is indicated at *x*. In following out my method I apply the prepared insole of Figs. 1 and 2 to the last 4 as in Fig. 3, draw the upper and lining inward around and over the margin of the last, and place the margins of the upper and lining directly against the outer surface of the molded flange 2, as in Fig. 3. I also place a welt 5 against the exterior of the upper as in said figure, and secure the welt, upper, lining, and insole together by a line of

30 35 40 45 50 55 60 65 70 75 80 85 90 95 100 105 110 115 120 125 130

stitches 6 passing through the entire thickness of the flange and located at the angle or bend of the latter, thereby forming the inseam, the result being as shown in Fig. 3. The flange serves as a guide during the stitching operation, and preserves or maintains the regularity of the stitching. I then trim off the margins of the welt, upper, lining, and molded insole-flange close to the inseam, as in Fig. 4, after which I flatten out the welt so as to cause it to stand out. I then apply a cushion 7 to the exposed outer surface of the insole, within the trimmed molded flange, and next apply an outer sole 8, fastening said outer sole to the welt by means of stitches 9 passing vertically through the welt and the sole 8 and constituting the outseam.

As a result of the step of making the insole with a molded flange as aforesaid by a simple bending operation without grooving or channeling into the thickness of the insole along the line of the bend, I am enabled to employ a thin insole of any convenient and suitable tough and flexible material, such for instance as cloth, which would not permit a cutting or channeling operation. Soft or chrome-tanned leathers may also be employed. By bending the insole without cutting or channeling, I am enabled to retain the entire strength of the material of the insole without diminution, and to get the benefit of the toughness of the grain side of the leather when that remains on the insole-blank, the grain being the toughest portion of the leather.

My method dispenses with the usual operation of channeling the insole to form a lip and a feather. It omits the feather altogether, but nevertheless enables the same overhang of the upper of the shoe to be attained that heretofore has necessitated the formation of a feather upon the insole of a welt shoe. It renders unnecessary the employment of channel-openers and the like and the sewing machine by which the inseam is sewed. It allows the use of an insole of extremely flexible material. The omission of a feather secures in the completed shoe the advantage that there is nothing to form a ridge beneath the wearer's foot, and to curl out of shape and hurt the foot.

As I have stated above, the flange of the insole serves as a guide during the stitching operation, and preserves or maintains the regularity of the stitching. The stitching is gaged from the inner angle of the bend of the flange with relation to the body of the insole, and the upper and lining are held close against the outer surface of the flange, thereby securing regularity in the shape of the shoe.

A shoe made by my method has extreme flexibility in the sole thereof, attained by so shaping the insole as to permit a firm inseam to be secured on stock that is unfitted or too thin to be channeled. The shoe is absolutely smooth inside, inasmuch as the edge of the insole is so secured to the welt and upper that the margin of the insole cannot turn up in course of drying after being moistened to form a ridge to hurt the wearer's foot.

I claim as my invention:—

1. The improved method of making a welt shoe which comprises the steps of taking a

- thin flexible insole-blank, producing an up-standing edge-flange or lip thereon by a bend around the margin of the said blank defining the extreme outer boundary of the tread-surface of the insole and so that a continuation of said tread-surface forms the exterior of the flange or lip at the bend, then applying the prepared insole to the central portion of the tread-surface of a last with the marginal portion of the latter tread-surface projecting outwardly beyond the outer margin of the tread-surface of the insole, then applying an upper to the last and bending it around the edge of the last, drawing it inward upon the exposed marginal portion of the tread-surface and last and against the continuation of the insole tread-surface immediately at the bend, and then applying a welt, stitching an inseam, trimming the inseam, applying an outsole, and connecting the outsole with the welt by an outseam.
2. The improved method of making a welt shoe which comprises the steps of taking a thin flexible insole-blank, producing an up-standing edge-flange or lip thereon by a bend around the margin of the said blank defining the extreme outer boundary of the tread-surface of the insole, with the whole substance of the insole extending to the said boundary and a continuation of the said tread-surface forming the exterior of the flange or lip, then applying the prepared insole to the central portion of the tread-surface of a last with the marginal portion of the latter tread-surface projecting outwardly beyond the outer margin of the tread-surface of the insole, then applying an upper to the last and bending it around the edge of the last, drawing it inward upon
- the exposed projecting marginal portion of the tread-surface of the last and against the continuation of the insole tread-surface immediately at the bend, then placing a welt against the flange of the upper, making an inseam, trimming the same, applying an outsole, and connecting the outsole with the welt by an outseam.
3. The improved method of making a welt shoe which comprises the steps of taking a thin flexible insole-blank, forming an up-standing edge-flange or lip thereon by a bend around the margin of the said blank defining the extreme outer boundary of the tread-surface of the insole and so as to change the direction of the continuation of such surface at the bend, then applying the prepared insole to the central portion of the tread-surface of a last having a rounded or chamfered marginal reduction of its tread-surface located externally with relation to the outer margin of the insole, then applying an upper to the last and bending it inward around and upon the rounded or chamfered marginal portion of the tread-surface of the last and against the outer surface of the flange of the insole, then placing a welt against the flange of the upper, then forming an inseam located inside the circuit of the rounded or chamfered margin, then trimming said inseam, then applying the outsole, and then connecting the outsole with the welt by an outseam.

In testimony whereof I affix my signature in presence of two witnesses.

FRANK W. MERRICK.
